CHAIR

Carl H. Oermann, York, Pa.

Application February 19, 1936, Serial No. 64,647

2 Claims. (Cl. 155—116)

This invention relates to chairs, particularly to self adjusting chairs of the type commonly used on steamers, beaches, lawns, etc.

An object of the present invention is to provide an improved chair of the above type which is easily adjustable to various reclining positions and is capable of being folded into a very compact condition when not in use or for transportation.

Another object of the invention is to provide an improved chair of the character mentioned, which is simple in construction, and reliable and exact in function under all conditions of service.

The invention also comprises certain new and useful improvements in the construction, arrangement and combination of the several parts of which it is composed, as will be hereinafter more fully described and claimed.

In the accompanying drawings:—

Figure 1 is a perspective of the frame of a chair constructed according to my invention, the fabric portion of the back and seat being omitted so as to show clearly the underlying structure;

Fig. 2 is an elevation looking at the rear of the chair;

Fig. 3 is a vertical longitudinal section taken on the line 3—3 of Fig. 2;

Fig. 4 is an enlarged elevation of a portion of the chair frame showing the manner in which the back and seat frame is adjustably mounted thereon, the seat and back frame being shown in one position by full lines and in two other positions by broken lines; and

Fig. 5 is a rear elevation of a portion of the structure shown in Fig. 4, showing the manner of pivotally connecting the back frame to the adjacent portion of the chair frame.

Referring to the drawings, the chair comprises front legs 11, positioned parallel to each other and connected by parallel rods 12 and 13 near the bottom and mid points, respectively. As is customary, the rods 12 and 13 are rigidly fixed in any suitable manner to the legs 11.

A pair of rear legs 14 are pivoted, by bolts or pins 15, to the upper ends of the front legs 11. The rear legs 14 extend rearwardly and downwardly at a suitable angle, and said rear legs are retained rigidly in position with respect to the front leg, by means to be hereinafter described. Near their bottom, the rear legs 14 are connected by a rod 16, which is rigidly fixed in any suitable manner to the rear legs 14.

Also pivoted to the pins 15, are the front ends of arm rests 17. These arm rests extend rear-

wardly, and, as is customary, lie in a substantially horizontal plane when the chair is set up.

The rear ends of the arm rests 17 are supported from the rear legs 14 by brace members 18. The upper ends of the braces 18 are pivotally connected to the rear ends of the arm rests 17 by bolts or pins 19, and the lower ends of the braces are connected by a rod 20.

As shown in Fig. 2, the rod 20 is mounted in openings 21 formed through the braces 18, and the ends of the rod 20 project a suitable distance beyond the braces 18, as indicated at 22. The rod 20 is rigidly fixed to the braces in any suitable manner, such as by nails 23.

Formed in each of the rear legs 14, at a suitable distance above the rod 16, is a notch 24. The projecting ends 22 of rod 20 are adapted to seat in the notches 24 to retain the frame of the chair in position as shown.

At a suitable distance above the rod 20, a second rod 25 connects the braces 18, being rigidly fixed to said braces in any suitable manner. The rods 20 and 25 are disposed substantially parallel, however, rod 25 does not project beyond the braces 18.

Mounted on rods 13 and 25, and disposed adjacent to the legs 11 and 14, are seat supporting members in the form of bars 26.

The bars 26 are positioned adjacent the inner surface of the legs 11, and the brace members 18 are interposed between the outer surface of the bars 26 and the inner surface of the rear legs 14. The arm rests 17 are positioned against the outside surfaces of the rear legs 14 and brace members 18. This arrangement permits the framework to be folded when the rod 20 is lifted out of the notches 24.

The seat comprises a frame composed of side rails 27 which are connected at the front by a rod 28, and connected at the rear by a rod 29.

The seat supporting bars 26 are arranged substantially parallel and the side rails 27 of the seat are also parallel and are superposed on the bars 26 so as to be wholly supported thereby, as shown in Figs. 1, 3, and 4. The side rails 27 are slidably mounted on the supporting bars 26 for forward and backward movement, and in its forward and backward movement the relative position of the seat with respect to the frame of the chair and especially the supporting bars 26 never changes. That is to say, since the seat frame rests on and is supported wholly by the bars 26, and said bars 26 are stationarily held in the chair frame when the chair is set-up, the side rails 27 of the seat frame will always remain in a sub-

stantially horizontal position, irrespective of the extended or retracted position of said seat frame, on the supporting bars 26, resulting from the seat frame being moved forwardly or backwardly by 5 an occupant of the chair.

The back of the chair comprises side members 30 pivotally mounted at their lower ends on the rear rod 29 of the seat frame. The side members 30 extend upwardly a suitable distance and are 10 connected, at a point adjacent their upper ends, by a rod 31.

The back is supported from the arm rests 17, by means of link devices 32, so constructed as 15 to permit tilting of the back in a plurality of positions.

As shown best in Figs. 4 and 5, each link device 32 comprises an elongated member, preferably formed from metal, and having an offset and laterally projecting upper end portion 33, which 20 is formed with a perforation by which the link is mounted on pivot pin 19.

A slot 34 is formed in the main body portion of link 32 in which is disposed a pin 37 carried by each side member 30 of the back. In lieu of 25 pin 37 any other equivalent member or device may be employed for connecting the side member 30 to link 32.

The upper end of slot 34 is formed with a notch 35 which extends outwardly with respect 30 to the slot. Intermediate of the slot 34, there is another notch 36 which also extends outwardly.

As shown in Figs. 1 and 4, when the back is in a slightly inclined position, the link devices 32 project outwardly from pivot pins 19 and notches 35 and 36 are disposed on the upper edge or upper side of the slots 34, in position to receive pin 37. When the back is lowered to a more reclined position, pin 37 will be disposed in the lower ends 38 of slots 34. The pins 37 will be retained in 40 position in the notches, due to the downward pressure exerted by the weight of the links 32, it being understood that said links are loosely pivoted on the pins 19 and normally tend to hang vertically downward from the pins 19.

45 The chair may be quickly folded into a fairly compact bundle for transportation or storage by simply lifting rod 20 out of the notches 24 and forcing the legs together. The particular construction described above, due to the arrangement 50 of the various parts, takes up a comparatively small floor space when set up or when folded.

As shown in Fig. 4, repositioning of the back 55 as above described, effects a simultaneous sliding movement of the seat frame upon supporting bars 26, and in sliding forwardly and backwardly on the bars 26, the side rails 27 of the seat frame will, at all times, rest upon the bars 26, irrespective of the position of the back frame of the chair. 60 This is due to the loose pivotal connection of the back with the arm rests 17, provided by link devices 32 and their associated parts.

As shown in Fig. 3, extending from front seat rod 28 to upper back rod 31 and fastened to said 65 rods and also to rod 25, is a strip of suitable fabric, such as canvas, duck, or the like. This

canvas provides a seat 40 and a back support 41 for an occupant of the chair.

The glide of the seat is limited by means of a loop member 42, fastened to front seat rod 28 and looped around rod 13, as shown in Fig. 3. 5 Loop member 42 may be formed from any suitable flexible material or fabric, such as canvas, duck, and the like.

The relative positions of the seat and back of the chair may be quickly shifted by simply lifting 10 the link devices 32 so as to move the pins 37 out of the notches in said link devices in which they are disposed and repositioning the pins 37 in other notches of the link devices 32. Fig. 4 illustrates several positions in which the back can be 15 set by shifting the links 32, as above described, and such movement of the back effects a corresponding shifting of the seat on its supporting bars 26.

Changes may be made in the details of construction and in the arrangement of the parts above described within certain limits without departing from the spirit of the invention.

Having thus described my invention, what I claim is:—

1. A chair of the type described comprising pivotally connected front and rear legs, arm rests also connected to said leg pivots, brace members pivotally connected to said arm rests and detachably connected to the rear legs near the 30 lower ends thereof, substantially horizontally disposed seat supporting bars connected to said front legs and to said brace members, pivotally connected back and seat frames of which the latter rests wholly on said seat supporting bars, said 35 seat frame being adapted to slide forwardly and backwardly on its supporting bars without any part separating therefrom, links pivotally connected to the arm rests, pins projecting from the back frame, slots formed in said links, and 40 notches formed in said slots for receiving said pins for retaining the back frame in a plurality of positions.

2. A chair of the type described comprising pivotally connected front and rear legs, arm rests 45 also connected to said leg pivots, brace members pivotally connected to said arm rests and detachably connected to the rear legs, substantially horizontally disposed seat supporting bars connected at their rear end to said brace members, a 50 tiered connecting the front legs for supporting the forward ends of said seat supporting bars, pivotally connected back and seat frames of which the latter is slidably mounted on said supporting bars whereby said seat frame is disposed in a 55 substantially fixed horizontal position at all times, links pivotally connected to the arm rests, pins projecting from the back frame, slots formed in said links and having means therein for receiving said back frame pins for retaining the back 60 frame in a plurality of positions, and a loop member carried by the seat frame and looped around said tie rod for limiting the movement of the seat frame on its supporting bars.

CARL H. OERMANN.
